Primary Examiner — Richard Edgar*Assistant Examiner* — Jessica Ruth Grable(74) *Attorney, Agent, or Firm* — JCIPRNET**CLAIM**

The ornamental design for a child bed, as shown and described.

DESCRIPTION

FIG. 1 is a front, right, top perspective view of a child bed showing our new design;

FIG. 2 is a front elevation view thereof;

FIG. 3 is a rear elevation view thereof;

FIG. 4 is a left side view thereof;

FIG. 5 is a right side view thereof;

FIG. 6 is a top view thereof; and,

FIG. 7 is a bottom view thereof.

The broken (dashed) lines in the drawings show portions of the child bed that form no part of the claimed design.
